CLAIM

The ornamental design for a storage container, as shown and described.

DESCRIPTION

FIG. 1 is a top plan view of a storage container showing my new design;

FIG. 2 is a left side elevational view thereof, the right side view being a mirror image;

FIG. 3 is a front elevational view of a storage container showing my new design;

FIG. 4 is a bottom plan view of a storage container showing my new design;

FIG. 5 is a rear elevational view of a storage container showing my new design; and,

FIG. 6 is a top perspective view in the open position of a storage container showing my new design.
